LAUNDRY IRONER

Claude J. West, Philadelphia, Pa., assignor, by
mesne assignments, to Theodore Halkias

Application November 28, 1936, Serial No. 113,092

13 Claims.

(Cl. 38—8)

The present invention relates to a laundry ironer and it relates more particularly to laundry ironers for commercial laundries.

One of the objects of the present invention is to obtain greater compactness as well as greater efficiency in laundering machines or laundry ironers of the mangle type, and also to improve the quality of the resultant product.

Other objects of the present invention will appear more fully from the following detailed description and accompanying drawings.

With the above and other objects in view, the present invention consists of a laundry ironer of the mangle type comprising a single roll and a pair of curved press platens pivoted beneath the roll and yieldably pressed against the same from opposite sides, and a pair of oppositely disposed feed-in and discharge conveyers above the respective steam chests and arranged to feed the work to and to receive the work from a relatively small uppermost uncovered zone of the roll.

The present invention further consists of other novel features which appear more fully from the following detailed description.

For the purpose of illustrating the invention, there is shown in the accompanying drawings one form thereof which is at present preferred, since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the accompanying drawings in which like reference characters indicate like parts:

Figure 1 represents a front elevational view of the apparatus embodying my invention, broken away in parts to show portions of the interior thereof in section; said view being taken while viewing the feed-in end of the machine.

Figure 2 represents a section on line 2—2 of Figure 1.

Figure 3 represents a section on line 3—3 of Figure 2.

Figure 4 represents an end elevational view indicating generally the right-hand end of Figure 1.

Figure 5 represents a similar left-hand end elevational view partly broken away to disclose the interior.

Figure 5a represents a section on line 5a—5a of Fig. 5.

Figure 6 represents a fragmentary top plan

view of one of the auxiliary feed drives or conveyor drives.

Figure 7 represents a fragmentary section on line 7—7 of Figure 6.

Figure 8 represents a fragmentary section on line 8—8 of Figure 6.

Figure 9 represents a perspective view of one of the terminal bearing brackets which give support to the stripper and auxiliary guide belts.

Figure 10 represents a perspective view of one of the stripper figures.

Figure 11 represents an end elevational view similar to that shown in Figure 7, illustrating a modified embodiment of the present invention with respect to the auxiliary guide belt.

The machine of the present invention includes a main roll designated generally by the numeral 14 having on opposite sides thereof press platens or steam chests designated generally by the numerals 15 and 16 pivoted at 17 and 18 respectively, beneath the main roll 14, and feed-in conveyor belt means designated generally by the numeral 19 and delivery conveyor belt means designated generally by the numeral 20 and auxiliary guide and stripper means 21 intermediate the conveyor means 19 and 20.

The main roll 14, as well as the platens or chests 15 and 16 are preferably of a sectional construction of the general type disclosed in Patent No. 2,057,988, issued October 20th, 1936, and are formed of a successive series of sections, as for instance, 16—a, 16—b, 16—c, 16—d and 16—e, depending upon the length of the machine desired or depending on the width capacity desired in the machine. The individual sections are suitably secured to each other and in alignment with each other by bolts or other suitable fastening means 22 and to the outermost sections (16—a and 16—e, for instance) the combined terminal trunnion and closure plates 23 and 24 are secured by suitable bolts 25. The trunnions 26 and 27, carried by the plates 23 and 24, respectively, are suitably journalled in roller bearings 28 and 29 and housed within suitable journal boxes or bearing housings 30 and 31, respectively, which are carried by transverse yokes 32 and 33 at the opposite ends of the machine. The bearing yokes 32 and 33 are preferably adjustably mounted on opposite terminal pedestals 34 and 35, respectively, whereby the axis of rotation of the main roll 14, may be adjusted, within a suitable range, both vertically as well as horizontally and with the adjustment being independent at the two trunnions.

To this end the opposite ends of the yokes 32

15

20

35

40

50

55

and 33 are provided with more or less suitably elongated vertical openings, into which supporting sleeves 36 pass; said sleeves 36 having the lower nut-like flanges 37 of enlarged diameter on which the yokes rest, and the sleeves being internally threaded and being threadedly carried by the screw-posts 38. By turning the nut-like flange 37 of the supporting sleeves 36, the yokes may be raised and lowered upon the screw-posts 38. Lock-nuts 39 are provided on the screw-posts directly above the yokes for locking and more firmly clamping the yokes in the desired position after the height has been adjusted by the turning of the sleeves 36.

For horizontal adjustment, adjusting screws or set screws 40 are provided in each end of the yoke, and bearing against the sleeves 36 for locking the yoke in any desired lateral adjustment.

To the upper ends of the screw posts 38, the brackets 41 and 42 are secured at the opposite ends of the machine by lower supporting nuts 43 and upper lock nuts 44 which bear against the lower and upper surfaces of the horizontal flanges 45 of said brackets.

The press-platens or chests 15 and 16 are also sectionally formed as indicated particularly in Figure 1 with the successive sections tied together by suitable tie bolts 41.

Each section is provided at one of its ends with an outwardly extending inlet lug or boss 48 and corresponding outlet lug or boss 49 containing suitable ports entering the interior steam space of the section. These successive inlet and outlet ports are then connected with each other through suitable tubing which may include siphon tubes 50, so as to prevent strain either on the pipe connections or upon the sections with variations in temperature. As indicated in Figure 1, this successive manifolding between successive ports forms, in effect, a single manifold at the top and a single manifold at the bottom of each of the sections, steam-chests or platens.

It will be observed that each section includes terminal webs or flanges 51 and 52; the webs 51 carrying the inlet and outlet port members and the webs 52 being perforated in registration with the inlet and outlet port members of the next adjacent section, so that the manifold fittings pass freely through the webs 52 in order to reach and to be connected in sealed relation to the inlet or outlet port member carried by the next adjacent web 51.

In the suitably thickened inner walls of the press platens or steam chests 15 and 16, horizontal vacuum or suction manifold openings 53 are provided which communicate with corresponding rows of suitably spaced suction recesses 54 in the curved, operative contact surfaces 55 of the platens, whereby steam or vapor produced in the work due to the heat, may find ready escape through these recesses and vacuum manifolds. In this respect, the steam chests or press platens are similar in construction to that disclosed in the patent above referred to.

The steam chests 15 and 16 are provided with a series of alternately staggered hinge or pivot projections 56 and 57, which cross each other and through which the steam chests are pivotally mounted upon the pivot rods or the pivot pins 17 and 18, respectively. The pivot pins or rods 17 and 18, respectively, are in turn carried by the stationary brackets or pedestals 58 and 59, respectively.

As shown particularly in Figure 2, the pivot flanges 56 and 57 cross each other, and extend

substantially beyond the curved operative surfaces of the respective steam chests which they support, both in an outward radial direction as well as in a circumferential direction, so that a tilting of the steam chest away from the roll 14 about the supporting pivot, will cause the entire curved operative surface of the steam chest to recede from the roll. Thus, it will be observed that each of the pivots 17 and 18 is at a substantially greater radial distance from the axis of the roll 14 and from the axis of the corresponding curved operative surfaces of the steam chests than said operative surfaces, and is removed a substantial extent in a circumferential direction from the end of the curved operative surface of the steam chest.

The steam chests 15 and 16 are yieldably pressed against the roll 14 by means of a series of helical compression springs 60, the lower ends of which rest in the trough-like U-iron beam 61 and the upper ends of which bear against the lower horizontal webs 62 of the steam chests. Preferably two springs 60 are provided beneath each section so as more or less evenly to distribute the sustaining force.

In order to permit of an adjustment of the pressure for varying kinds of work and also to permit the complete retraction of the steam chests, as for instance, when the machine is not in operation, the spring-carrying U-beam 61 is adjustably supported upon a series of screw posts 63, which are threaded through suitable nut-like sleeve 64 extending through the horizontal web of the U-channel 61 at suitable points, and locked therein by the lock nuts 65. The screw posts 63 are provided with a bottom trunnion portion 66 which extends into the inner portion of the ball-thrust bearings or roller thrust bearings indicated at 67, and the thrust flange 68, which rests upon said thrust bearing 67, thereby to give the screw post 63 a bottom journal both for radial support as well as for vertical thrust support. The bearing 67 may be suitably housed in any suitable bearing housing 69 carried in the base 70 of the machine. By turning the screw post 63 in either direction, the screw post is caused to thread into or out of the nut-like sleeve 64 to a greater or lesser extent and thus raise and lower the U-beam 61.

The central post 63 indicated in Figure 1 is provided also with a spanner disc 71, into the holes of which a spanner wrench or rod may be inserted, whereby it may be turned more readily.

The successive screw posts 63 are then permanently re-connected by sprocket wheels 72 and 73 and 74 and 75, and intermediate sprocket chains 76 and 77, whereby all the screw posts can be caused to revolve in unison with each other, so that a uniform adjustment is maintained throughout the length of the steam chest.

To the trunnions 26 and 27 of the roll 14, hubs 78 and 79 are suitably keyed; said hubs in turn carrying similar gears 80 and 81 for driving the feed-in and delivery conveyers and also the auxiliary guides. On one of the trunnions, as, for instance, on the trunnion 27, the hub 79 is also provided with the sprocket wheel 82 through which the entire machine may be driven from any suitable source of power by the sprocket chain 83 driven from the sprocket pinion 84. The sprocket pinion 84 may be directly from a motor or it may be from a reducing gear mechanism associated with the motor. Neither the motor nor the reducing gear mechanism is here shown in detail and they may be of any conventional construc-

tion; the only element indicated being the shaft 85 which carries the sprocket pinion 84 and the bearing 86 in which said shaft is journaled.

The brackets 41 and 42 carried upon the screw-posts 38 at opposite ends of the machine, support between them a pair of horizontal parallel rods 87 and 88, as indicated particularly in Figures 3 and 6 which rods serve to carry similar drive mechanisms at opposite ends of the machine for driving both the feed-in as well as the delivery belts, and also to drive the auxiliary drive belts.

Thus, at each end of the machine, similar brackets 89 are pendently supported by means of the hangers 90 which are carried on said rods 87 and 88, said brackets having journaled therein a central shaft 91 which carries a driven pinion 92 at its outer end, in mesh with the respective driving gears 80 and 81 and also carries a driving sprocket gear 93 over which a sprocket chain 94 travels; said sprocket chain 94 travelling over a pair of driven sprocket wheels 95 and 96, respectively, also journaled on said brackets 89, thereby providing three similarly rotating shafts 91 and 97 and 98, respectively. From each of these shafts 91, 97 and 98, similar flexible shaft connections 99, 100 and 101 extend so as to provide flexible driving connections to the feed-in belts, the delivery belts and the auxiliary guide belts.

The feed-in belts and the delivery belts 102 and 103, respectively, are carried by similar driven rolls 104 and 105, and idle rolls 106 and 107. The driven rolls 104 and 105 carried by the shafts 108 and 109, respectively, derive their driving power from the flexible shafts 100 and 101, respectively, as indicated in Figure 6, and are journaled in vertical bearing slots 110, in a series of similar separated and supporting webs 111, so that the rolls 104 and 105, together with their respective shafts 108 and 109 may adjust themselves vertically for varying thicknesses of work.

The somewhat lower idle rolls 106 and 107 are carried by suitable idle pins or idle shafts 112 and 113. These idle pins or shafts 112 and 113 may be loosely journaled in the more or less horizontally, though downwardly inclined, slots 114 provided in the separated and supporting flanges 111; the lower idle rolls 106 and 107 being made sufficiently heavy so that they will adequately tension the belts 102 and 103 by their own weight. If desired, however, the belts 102 and 103 may be otherwise tensioned as, for instance, by carrying the pins 112 and 113 in suitable screw-adjusted and screw-locked brackets. Between the upper and lower portions of the belts 102 and 103 wooden supporting blocks 115 and 116 may be provided to give support to the upper portions of the belts so that they will not unduly sag when pressure is applied to them from above, as for instance that incident to the application of the work on the belt 102 and the removal of the work from the belt 103. These wooden blocks 115 and 116 may be carried on suitable tie rods 117, extending therethrough and also extending through the separated and supporting webs or flanges 111.

From the rods 87 and 88, a series of brackets 118 are suspended, as indicated at 119, in Figures 6, 7 and 9, said brackets including aligned pivot apertures 120, 121, 122 and 123 through which the idle pivot rods 124, 125, 126 and 127 extend, and also includes a vertical bearing slot 128 in which the shaft 129 is loosely journaled in such a way that it may ride up and down and thus adjust itself vertically.

The shaft 129 carries a series of driving rolls 130, which serve not only to drive the belt 131 but

also serve as a take-up roll by resting on the belt and being supported by a free span of the belt. The belt 131 extends over idle rolls 132, 133, 134 and 135, carried by the pivot pins or shafts 124, 125, 126 and 127, respectively. The centers of the pins 124, 125, 126 and 127 are so located on the brackets 118 that the belt spans intermediate the additional rolls 134 and 132 on one hand, and intermediate the additional rolls 135 and 133 on the other hand, will bear against the belts 102 and 103, respectively, as they pass over the driving rolls 104 and 105, respectively, as indicated in Figures 2, 6 and 7.

In this way, the work entering on the top of the belt 102 is guided around on the belt 102 until it reaches the main roll 114 and is then guided by the main roll 114 in between said roll and the operative surface of the steam chest 15. In this way also the work leaving the steam chest 16 is guided around the belt 103 so that it may be carried away by the upper surface of the belt 103.

In order to insure that the finished work will properly separate from the roll 14 and be engaged by the belts 103 and 131 (where these belts contact with each other), stripper fingers 136 are also provided pivotally supported upon the rods 126 at the pivot holes 137, which fingers may be further provided with arcuate slots 138 (centered about the holes 137), through which slots 138 the pivot rods 127 extend, so as to limit the downward deflection of the fingers 136.

In Figure 11 a modified form of construction is shown in relation to the auxiliary guiding belt whereby the entire guiding belt mechanism including the stripper fingers may be tilted upwardly into an inoperative position as shown in Figure 11. In this modified form of construction the rods 87 and 88 are not supported directly on the brackets 41 and 42, but are instead carried by the brackets 118, and the brackets 118 are in turn provided with a further pivot member 140 pivotally supported on the pivot rod 141. The pivot rod 141 is in turn carried by similar pivot brackets 142, carried by the brackets 41 and 42. In this way by tilting the entire mechanism upward the pinions 92 are raised out of mesh in relation with the gears 80 and 81.

The roll 14 is preferably covered with one or more layers of suitable fabric covering 143 which are tightly wrapped around the roll; these fabric coverings being suitably woven and of suitable surface finish.

The steam inlet manifolds 50 are connected through a suitable pipe 144 to a suitable source of steam supply, while exhaust manifolds are similarly connected through a pipe 145 either to a discharge or to a steam return, depending on whether the waste steam or condensate is to be re-used.

Likewise, the suction manifold passageways are connected through suitable flexible conduits 146 to a vacuum manifold 147 which in turn may be connected to a suitable vacuum pump (not shown), of any desired construction (either a mechanical type vacuum pump or a Venturi vacuum pump). However, it should be noted that as the steam generated in the laundry passing between the rolls itself produces some pressure, it is at times possible to operate the machine with but very little vacuum, because the steam issuing from the laundry tends to escape through the vacuum passageways with comparatively little actual suction exerted on such passageways.

The outer surfaces of the steam chest are preferably insulated by a suitable body of insulating

material 148 which is retained in place by a covering plate 149, secured to the steam chest.

Likewise, the driving mechanisms may be enclosed in suitable metallic shields or housings 150 5 and 151, with suitable terminal plates 152 which may be removably attached by screws 153 for more ready access to the adjustments of the main bearings and the other driving mechanisms.

The present invention may be embodied in other 10 specific forms without departing from the spirit or essential attributes thereof, and it is therefore desired that the present embodiments be considered in all respects as illustrative and not restrictive, reference being had to the appended 15 claims rather than to the foregoing description to indicate the scope of the invention.

Having thus described the invention, what is hereby claimed as new and desired to be secured by Letters Patent, is:

20 1. A laundry ironing machine comprising a single main roll, a pair of generally concavely surfaced press platens arranged yieldably to bear against said roll, said press platens being disposed at opposite sides of said roll and having the concave surfaces thereof in operative juxtaposition to a generally uninterrupted major portion of the periphery of said roll, and said press platens being spaced from each other at the top of the roll, thereby to leave a portion of the roll exposed 25 at the top, a feed-in belt above one of said press platens arranged to feed the work to said exposed portion of the roll, and a delivery belt above the other of said press platens arranged to receive the work from said exposed portion of the roll 30 and to deliver the same.

35 2. A laundry ironing machine comprising a single main roll, a pair of generally concavely surfaced press platens adapted to bear against said roll, said press platens being disposed at opposite sides of said roll and having the concave surfaces thereof in operative juxtaposition to a generally uninterrupted major portion of the periphery of said roll, said press platens being spaced from each other at the top of the roll, thereby to leave a portion of the roll exposed at 40 the top, a feed-in belt above one of said press platens arranged to feed the work to said exposed portion of the roll, yieldable means for accommodating work of varying thickness between said feed-in belt and said roll, said yieldable means being disposed near the discharge end of said feed-in belt, and a delivery belt above the other of said press platens arranged to receive the work from said exposed portion of the roll and to deliver the same.

45 3. A laundry ironing machine comprising a single main roll, a pair of generally concavely surfaced press platens arranged yieldably to bear against said roll, said press platens being disposed at opposite sides of said roll and having the concave surfaces thereof in operative juxtaposition to a generally uninterrupted major portion of the periphery of said roll, said press platens being spaced from each other at the top of the roll, thereby to leave a portion of the roll exposed at 50 the top, a feed-in belt above one of said press platens arranged to feed the work to said exposed portion of the roll, a delivery belt above the other 55 of said press platens arranged to receive the work from said exposed portion of the roll and to deliver the same, and a series of stripping fingers frictionally engaging the periphery of said main roll at the delivery end thereof, said fingers being 60 constructed and arranged to strip the work from 65 the roll and guide it into cooperative engagement with said delivery belt.

4. A laundry ironing machine comprising a single main roll, a pair of generally concavely surfaced press platens adapted to bear against said roll, said press platens being disposed at opposite sides of said roll and having the concave surfaces thereof in operative juxtaposition to a generally uninterrupted major portion of the periphery of said roll, said press platens being spaced from each other at the top of the roll, thereby to leave a portion of the roll exposed at the top, a feed-in belt above one of said press platens arranged to feed the work to said exposed portion of the roll, yieldable means for accommodating work of varying thickness between said feed-in belt and said roll, said yieldable means being disposed near the discharge end of said feed-in belt, a delivery belt above the other of said press platens arranged to receive the work from said exposed portion of the roll and to deliver the same, and a series of stripping fingers frictionally engaging the periphery of said main roll at the delivery end thereof and constructed and arranged to strip the work from the roll and 10 guide it into cooperative engagement with the delivery belt.

5. In a laundry ironing machine, a driven endless feeder belt arranged to discharge work into the intake of said ironing machine, a driven endless delivery belt arranged to receive the ironed work from said ironing machine, an intermediate auxiliary belt disposed between said feeder belt and said delivery belt, said intermediate auxiliary belt being constructed and arranged substantially to contact said feeder belt near the discharge end thereof and also substantially to contact said delivery belt near the receiving end thereof, whereby said contacting belts may positively grip and feed work into and positively grip 15 and deliver work from said ironing machine, and yieldable means for tensioning said auxiliary belt whereby work of varying thickness may be accommodated.

6. A laundry ironing machine comprising a single main roll, a pair of generally concavely surfaced press platens arranged yieldably to bear against said roll, said press platens being disposed at opposite sides of said roll and having the concave surfaces thereof in operative juxtaposition to a generally uninterrupted major portion of the periphery of said roll, a driven endless feeder belt arranged to discharge work into the intake of said ironing machine, a driven endless delivery belt arranged to receive the ironed work from said ironing machine and an intermediate auxiliary belt disposed between said feeder belt and said delivery belt, said intermediate auxiliary belt being constructed and arranged substantially to contact said feeder belt near the discharge end thereof and also substantially to contact said delivery belt near the receiving end thereof, whereby said contacting belts may positively grip and feed work into, and positively grip and deliver work from said ironing machine, and yieldable means for tensioning said auxiliary belt whereby work of varying thickness may be accommodated.

7. A laundry ironing machine comprising a single main roll, a pair of generally concavely surfaced press platens arranged yieldably to bear against said roll, said press platens being disposed at opposite sides of said roll and having the concave surfaces thereof in operative juxtaposition to a generally uninterrupted major por- 70 75

- tion of the periphery of said roll, a driven endless feeder belt arranged to discharge work into the intake of said ironing machine, a driven endless delivery belt arranged to receive the ironed work from said ironing machine and an intermediate auxiliary belt disposed between said feeder belt and said delivery belt, said intermediate auxiliary belt being constructed and arranged substantially to contact said feeder belt near the discharge end thereof and also substantially to contact said delivery belt near the receiving end thereof, whereby said contacting belts may positively grip and feed work into, and positively grip and deliver work from said ironing machine, yieldable means for tensioning said auxiliary belt whereby work of varying thickness may be accommodated, and a series of stripping fingers frictionally engaging the periphery of said main roll at the delivery end thereof, said fingers being constructed and arranged to strip the work from the roll and guide it into cooperative engagement between said auxiliary belt and said delivery belt.
3. In a laundry ironing machine, a driven endless feeder belt arranged to discharge work into the intake of said ironing machine, a driven endless delivery belt arranged to receive the ironed work from said ironing machine and an intermediate auxiliary belt disposed between said feeder belt and said delivery belt, said intermediate auxiliary belt being constructed and arranged substantially to contact said feeder belt near the discharge end thereof, and also substantially to contact said delivery belt near the receiving end thereof, whereby said contacting belts may positively grip and feed work into and positively grip and deliver work from said ironing machine, said intermediate auxiliary belt being supported on rolls journaled at each of their respective ends in pivotally supported brackets, said brackets being pivotally swingable away from said machine, whereby said auxiliary belt may be swung away from and out of cooperative engagement with said feeder belt and said delivery belt to provide access to the interior of said laundry ironing machine between said feeder belt and said delivery belt.
9. A laundry ironing machine comprising a single main roll, a pair of generally concavely surfaced press platens adapted to bear against said roll, said press platens being disposed at opposite sides of said roll and having the concave surfaces thereof in operative juxtaposition to a generally uninterrupted major portion of the periphery of said roll, and said press platens being spaced from each other at the top of the roll thereby to leave a portion of the roll exposed at the top, a feed-in belt above one of said press platens arranged to feed the work to said exposed portion of the roll, a delivery belt above the other of said press platens arranged to receive the work from said exposed portion of the roll and to deliver the same, and yieldable means arranged to permit work of varying thickness to be passed operatively between said roll and said delivery belt, said yieldable means being disposed near the receiving end of said delivery belt.
10. A laundry ironing machine comprising a single main roll, a pair of generally concavely surfaced press platens adapted to bear against said roll, said press platens being disposed at opposite sides of said roll and having the concave
- surfaces thereof in operative juxtaposition to a generally uninterrupted major portion of the periphery of said roll, said press platens being spaced from each other at the top of the roll, thereby to leave a portion of the roll exposed at the top, a feed-in belt above one of said press platens arranged to feed the work to said exposed portion of the roll, a delivery belt above the other of said press platens arranged to receive the work from said exposed portion of the roll and to deliver the same, and yieldable means arranged to permit work of varying thickness to be passed operatively between said roll and said delivery belt, said yieldable means being disposed near the receiving end of said delivery belt.
11. A laundry ironing machine comprising a single main roll, a pair of generally concavely surfaced press platens disposed at opposite sides of said roll and having the concave surfaces thereof in operative juxtaposition to a generally uninterrupted major portion of the periphery of said roll, said press platens meeting beneath said roll and each of said press platens being pivotally supported in proximity to the adjacent portions thereof, the outer lower extremities of each of said press platens being vertically supported by yieldable spring cushioned means whereby work of varying thickness may be ironed between said main roll and each of said pivotally supported spring-cushioned press platens.
12. A laundry ironing machine comprising a single main roll, a pair of generally concavely surfaced press platens disposed at opposite sides of said roll and having the concave surfaces thereof in operative juxtaposition to a generally uninterrupted major portion of the periphery of said roll, said press platens meeting beneath said roll and each of said press platens being pivotally supported in proximity to the adjacent portions thereof, the outer lower extremities of each of said press platens being supported by vertically adjustable supporting means, whereby the ironing pressures between said press platens and said main roll may be adjusted at will.
13. A laundry ironing machine comprising a single main roll, a pair of generally concavely surfaced press platens disposed at opposite sides of said roll and having the concave surfaces thereof in operative juxtaposition to a generally uninterrupted major portion of the periphery of said roll, said press platens meeting beneath said roll and each of said press platens being pivotally supported in proximity to the adjacent portions thereof, the outer lower extremities of each of said press platens being supported by vertically adjustable supporting means, whereby the ironing pressures between said press platens and said main roll may be adjusted at will, and yieldable spring-cushioned means interposed between said vertically adjustable supporting means and said press platens whereby work of varying thickness may be ironed between said main roll and each of said pivotally supported spring-cushioned press platens.
